(57) **CLAIM**

The ornamental design for a channel element for displaying graphics, as shown and described.

DESCRIPTION

FIG. 1 is a front perspective view of a channel element for displaying graphics showing my new design;

FIG. 2 is a left side elevational view thereof, the right side elevational view being the mirror image thereof;

FIG. 3 is a top elevational view thereof;

FIG. 4 is a bottom elevational view thereof;

FIG. 5 is a rear elevational view thereof; and,

FIG. 6 is a front elevational view thereof.

The break lines shown in FIGS. 1, and 3-6 indicate indeterminate length and form no part of the claimed design.
